UNITED STATES PATENT OFFICE.

THOMAS L. BARLOW, OF BOSTON, ASSIGNOR OF ONE-HALF TO FARRINGTON MCINTYRE, OF QUINCY, MASSACHUSETTS.

WINDOW-AWNING.

SPECIFICATION forming part of Letters Patent No. 355,370, dated January 4, 1887.

Application filed May 17, 1886. Serial No. 202,424. (No model.)

To all whom it may concern:

Be it known that I, THOMAS L. BARLOW, of Boston, in the county of Suffolk and State of Massachusetts, have invented new and useful 5 Improvements in Window-Awnings, of which the following is a specification.

This invention is an improvement upon the window-awning for which Letters Patent of the United States were granted to me May 12, 10 1885, said Letters Patent being numbered 317,485.

In the accompanying drawings, in which similar letters of reference indicate like parts, Figure 1 is a perspective view of a window-15 awning embodying my improvements in position for use upon a window. Fig. 2 is a vertical section of the same. Fig. 3 is an elevation of the window-awning closed, looking from the outside. Fig. 4 is a similar elevation, looking from the inside. Fig. 5 is an enlarged detail perspective. Fig. 6 is an inside view showing one of the wings or side pieces in the position it would assume if the entire awning were spread open flat.

25 A represents the frame or casing of the window; A', the upper and A" the lower sash. B is the central portion, and B' the side portion or wings, of the fabric or textile portion of the awning. This is secured to two cross-bars, of 30 which C is the upper and C' the lower, said cross-bars being connected by the jointed rods D and D'. The upper ends of these jointed rods, which are preferably metallic, are formed into sockets D'', of substantially the shape. 35 shown in Fig. 5, said sockets embracing and holding the opposite ends of the upper cross-bar, C. The lower ends of the jointed rods are formed into sockets D''', embracing and holding the opposite ends of the lower cross-bar, 40 C'. Extending horizontally from the sockets D'' are pivots or pins E, which support the awning by lying in screw-eyes e, which screw vertically into the upper portion of the casing.

The jointed rods are further provided near 45 their upper ends, next below the sockets D'', with two perforations, d and d', (see Fig. 5,) said rods being enlarged at that point for the purpose, and at their lower ends with two similarly-produced perforations, b and b'.

50 H H are rods for supporting the sides of the awning and holding the latter at a proper dis-

tance from the window when opened, said rods freely swinging from the perforations b, and passing through grommets or eyelets h, made in the sides or wings B'. These rods are provided with hooks H' at their free ends, which rest in screw-eyes g, secured to the inner sides of the casing. 55

In practice the lower end of the awning is, after the hooks H' are dropped into the screw-eyes, caught over the ends of said hooks by means of the grommets or eyelets h', as seen in Figs. 1 and 2, whereby the sides or wings of the awning are kept taut and smooth. In order to prevent said sides from slipping on the 60 rods H toward the center part of the awning by means of the grommets h, a bend or shoulder, H'', is formed in each rod, near the position of said grommet when the wings are spread. A rod, I, is secured horizontally and 65 continuously to the central portion, B', of the awning, and extends across said portion on a line with the joints of the rods D D'. 70

J is a cord secured loosely to the rod H, attached to the jointed rod D, extending across 75 and passing through the perforation b' in the opposite rod, D', thence through a slit in the awning and up and through another slit inside, thence through the perforation d in the rod D', across the awning, through the corresponding perforation, d, in the opposite rod, D, thence through a slit in the fabric and down, 80 hanging on the outside of the awning next the wing on that side.

The cord J' is secured loosely to the rod H, 85 attached to the jointed rod D', and extends across through the perforation b' in the rod D, out through the slit in the awning and in through another slit in the upper portion of the same, and then out through the perforation d in the rod D, being the same perforation through which the cord J passes out, (see Fig. 5,) so that both cords J and J' pass out and hang down on the same side. 90

K is a cord secured tightly to the bar I, near 95 one end thereof, and passing up and through the perforation d' in the rod D, from the outside inwardly, as shown in Fig. 5, thence across the awning, as shown in Fig. 1, through the perforation d in the rod D', and outside. K' 100 is a cord similarly secured to the opposite end of the rod I, and passing directly up and through

the same perforation, d' , through which the cord K passes. These two cords K and K' hang upon one side of the awning, and are tied together at their ends, and the cords J and J' hang upon the other side of the awning, and are not tied together. (See Figs. 3 and 4.)

To raise and fold the awning, first, the ends of the wings are slipped off the hooks H'; then one of the rods H is unhooked, and the cord 10 secured to that rod is pulled down, with the effect of folding the wing B' next said rod against the inside of the awning; then the opposite rod, H, is unhooked and its cord pulled upon, with the effect of folding its wing B' 15 against the other wing. The entire awning is next folded up inwardly by pulling simultaneously on the cords J J', (first slightly bending out the rods D D' at their joints,) and securing said cords in the ordinary manner to 20 the window-easing, and then by drawing on the cords K K' the horizontal rod I is raised, (its two ends equally,) with the effect of drawing the fabric of the awning upward and bunching it, as shown in Figs. 3 and 4, thus reducing 25 the obstruction of light at the window to a minimum when the awning is not in use.

When the awning is folded, the blinds are free to be opened and closed, as stated in the patent above referred to.

30 Having thus fully described my invention, what I claim, and desire to secure by Letters Patent, is—

1. The combination, with the jointed rods D D' and the fabric of the awning, of the cen-

tral horizontal rod, I, adapted to be raised by 35 suitable cords, substantially as and for the purpose set forth.

2. The combination, with the rods D D' and sides or wings B', provided with the openings h, of the swinging rods H, provided with the 40 bends or shoulders H'', substantially as and for the purpose described.

3. The rods D D', provided with the sockets D'' and D'', embracing the upper and lower 45 cross-pieces, substantially as and for the purpose set forth.

4. The rods D D', provided with the perforations d d' and b b', for accommodating the cords used in operating the awning, substantially as and for the purpose described. 5c

5. The rods D D', provided with the sockets D'' and pivots or pins E, in combination with bearings attached to the casing for supporting said pivots or pins, substantially as and for the purpose set forth. 55

6. The combination of the jointed rods D D', provided with the sockets D'' D'', perforations d d' b b', and pivots E, the cross-pieces C C', the rods H, provided with the shoulders H'' and hooks H', the horizontal rod I, awning 60 fabric B B', provided with the grommets or eyelets h h', and cords J J' K K', substantially as and for the purpose described.

THOMAS L. BARLOW.
